UNITED STATES PATENT OFFICE.

ERICK G. WALLINDER, OF DULUTH, MINNESOTA.

TABLE.

Application filed May 31, 1921. Serial No. 473,818.

To all whom it may concern:

Be it known that I, ERICK G. WALLINDER, a citizen of the United States, residing at Duluth, in the county of St. Louis and State 5 of Minnesota, have invented certain new and useful Improvements in Tables, of which the following is a specification, reference being had therein to the accompanying drawing.

10 This invention relates to tables and has special reference to one which may be conveniently knocked down, rendering it intermittently useful for special occasions such as banquets, picnics, or the like.

15 The principal object of the invention is to produce as practical, durable and convenient a device of this character as is possible.

Other minor objects and advantages will appear in the further disclosure.

20 Referring now to the accompanying drawing, in which like reference characters indicate like parts:

Figure 1 is an under side perspective view of a table top showing a broken leg structure 25 attached thereto.

Figure 2 is a vertical sectional view through the top of a table adjacent one side thereof.

Figure 3 is a broken side elevation of the 30 cooperatively united ends of two tables illustrating the manner in which an extension table may result from the use of the invention.

Figure 4 is a top plan view of one of the 35 leg sections folded.

The invention resides in the novel form of foldable collapsible leg section and the manner of applying same to the under side of a table top, the latter being either in 40 single form, or as a table having two sets of legs, or an indefinitely extendible table.

Each leg section comprises two pairs of legs, those of each pair being spaced apart by suitable cross bars 1 and 2, the legs being 45 indicated at 3 and 4, and the bars are spaced inwardly from both the upper and lower ends of one pair of the legs, while in the other cooperative pair of legs the bar 1 extends transversely the upper ends of the legs 50 and slightly therebeyond. This bar rests directly upon the upper face of the bar 1 of the other pair of legs, while the bar 2 of the latter pair of legs rests upon the upper face of the bar 2 of the other pair of legs and 55 centrally of the cross bars thus engaged they are united by through pins or bolts 5, which

result in two pairs of legs being pivotally united forming what is referred to as a leg section and separable from the table top.

The uppermost cross bar 1 which extends 60 beyond the legs is bevelled or inclined as at 6 and upon the under side of the table to which these legs are applied are fixed spaced cleats 7, they having their inner opposed faces inclined similar to that of the ends 6 65 of the cross bar so that when the latter is brought in contact with the under side of the table top in a position diagonally to the straight line of the cleats 7 and turned upon its pivotal bolt 5 until at right angles with 70 the cleats the inclined ends of the cross bar will be wedged in under the inclined edges of the cleats and thus securely held. This it is understood can only occur after the upwardly extending ends of the other pair of 75 legs are positioned outside of two straight edged cleats 8 and 9, properly spaced from each other diametrically opposite to the cleats 7 and the upper ends of this pair of legs are slotted as at 10 to provide certain 80 elasticity thereto for the tight and snug fitting thereof over the cleats, and the outer lower corner of the latter may be slightly rounded or bevelled to assist in such snug fitting.

When a leg section is thus fastened to the under side of a table it is quite obvious that the same forms an admirable, staunch support for the table top and one that may be quickly and conveniently adjusted to or 90 from the table.

When it is desired to provide for an extension table, that is where a plurality of tops are used in conjunction with a suitable number of leg sections, each table top is provided with an extra transverse cleat 11 spaced from the end of the table just one-half the width of the bar 1 of the leg section the ends of which are inclined and the spacing of the cleats 8 and 9 from the cleat 11 are such that when the leg section is applied to the abutting ends of two table tops as in Figure 3 the legs having resilient ends will occur back of the cleats 9, thus forming a holding union with same to prevent longitudinal movement of the tops and the wedging cleat will occur intermediate of the cleats 11 on the two abutting tops.

When two or more table tops are united in this way, the opposite ends of the extension thus made would be supported upon one of the leg sections attached in the usual

manner as heretofore described, thus producing a substantial extension table of any desired length.

Having thus described my invention, 5 what I claim and desire to secure by Letters Patent, is:

1. A collapsible extension table of the character described comprising a plurality of individually complete table tops, groups 10 of cleats upon the under side of each table top adjacent the ends thereof, detachable foldable leg sections each comprising four legs, and means whereby certain leg sections may be cooperatively united with certain of 15 the cleats adjacent the abutting ends of the table tops for cooperatively supporting and holding said tops together and other of the leg sections engageable with cleats at the opposite ends of the table tops.
2. A table of the character described comprising a top having a group of four cleats fastened to the under side thereof, two of 20 said opposed cleats having leg engaging sides straight and at right angles to the bottom of the table top, the other two of 25 said opposed cleats having straight leg engaging faces inclined at an acute angle to the table top, a detachable leg section comprising a pair of foldably united legs the 30 upper opposed ends of two of which are beveled for cooperative engagement with the inclined cleats, and the other two opposed upper ends of the leg section overlapping the straight sided cleats, substantially 35 as described.
3. A table of the character described com-

prising a top having a group of four cleats rigidly fixed to the under side thereof, a detachable leg section comprising a pair of foldably united legs, means at the upper 40 ends of one pair of legs for overlapping engagement with two of the spaced cleats and means upon the upper ends of the other pair of legs whereby the leg section may be securely attached to the table top by a 45 rotative action of one pair of the legs in the section.

4. An extendible table of the character described comprising a plurality of elongated individually complete tops, groups of 50 spaced leg engaging cleats upon the under side of each top and adjacent the ends thereof, detachable foldable leg sections having means for cooperative wedging engagement with two of the opposed spaced cleats 55 and overlapping engagement with the other opposed cleats in each group, an additional transverse cleat adjacent each end of each top but spaced sufficiently therefrom to receive the wedging member of one of the 60 leg sections therebetween when two of the table tops abut and the opposite leg members overlap the outermost cleats of the groups to form a cooperative leg support for the abutting ends of the table tops. 65

In testimony whereof I hereunto affix my signature in the presence of two witnesses.

ERICK G. WALLINDER.
